US00D882632S

(12) **United States Design Patent** (10) Patent No.: **US D882,632 S**
Alonso Ruiz et al. (45) Date of Patent: **** Apr. 28, 2020**

(54) **DISPLAY SCREEN OR PORTION THEREOF WITH GRAPHICAL USER INTERFACE**(71) Applicant: **Apple Inc.**, Cupertino, CA (US)(72) Inventors: **Marcos Alonso Ruiz**, San Francisco, CA (US); **Patrick Lee Coffman**, San Francisco, CA (US); **Alan C. Dye**, San Francisco, CA (US); **Stephen O. Lemay**, Palo Alto, CA (US); **Raymond Sepulveda**, San Jose, CA (US)(73) Assignee: **Apple Inc.**, Cupertino, CA (US)(***) Term: **15 Years**(21) Appl. No.: **29/703,244**(22) Filed: **Aug. 26, 2019****Related U.S. Application Data**

(63) Continuation of application No. 29/606,445, filed on Jun. 5, 2017, now Pat. No. Des. 857,739.

Primary Examiner — Melanie H Tung*Assistant Examiner* — Bao-Yen T Nguyen(74) *Attorney, Agent, or Firm* — Sterne, Kessler, Goldstein & Fox P.L.L.C.(57) **CLAIM**

The ornamental design for a display screen or portion thereof with graphical user interface, as shown and described.

DESCRIPTION

FIG. 1 is a front view of a first embodiment of a display screen or portion thereof with graphical user interface showing the claimed design; and,

FIG. 2 is a front view of a second embodiment of a display screen or portion thereof with graphical user interface showing the claimed design.

The outermost dashed broken lines in the figures show a display screen or portion thereof, and form no part of the claimed design. The other broken lines in the figures show portions of the graphical user interface that form no part of the claimed design.
